UNITED STATES PATENT OFFICE.

EDWIN G. GETTINS, OF LOS ANGELES, CALIFORNIA, ASSIGNOR TO MINNIE RUTH
GETTINS, OF LONG BEACH, CALIFORNIA.

AIRPLANE.

Application filed October 5, 1920. Serial No. 414,865.

To all whom it may concern:

Be it known that I, EDWIN G. GETTINS, a citizen of the United States, and a resident of Los Angeles, in the county of Los Angeles and State of California, have invented certain new and useful Improvements in Airplanes, of which the following is a specification.

This invention has reference generally to airplanes, flying machines, gliders, kites, airships and toys of these types; and the present invention has for its principal object to provide inherent lateral stability by means of intersecting planes at the lateral extremities of the main planes, and a disposition of all parts such as will bring the center of gravity of the whole airplane below the geometric central axis of the main planes. I attain these objects by means of the device shown in the accompanying drawings, in which:—

Figure 1 is a front elevation of a glider.
Figure 2 is a side elevation of the device.

Figure 3 is a view similar to that illustrated in Fig. 1, except that it is tipped at an angle laterally, and provided with certain reference characters for further explanation in a following description.

Figure 4 is a fragmentary detail perspective view of the lateral extremities of the wings or planes.

Figure 5 is a top plan view of the device.

The Fig. 1 is a clear illustration of the principal parts of the device, as the fuselage 17, landing gear 18, a rudder 14, a horizontal stabilizer 16, with or without elevators attached, a pair of wings 7, held in position by vertical struts 19, and carrying crossed auxiliary planes 4, or the intersection of the continuation of planes 7.

Referring to Fig. 3, the machine is shown tipped at an angle laterally. Gravity acts upon the planes thru the center of gravity 3, while the sustaining force of the air 1, upon the cross planes 4, which are in a nearly horizontal position, one at each end, exerts an equal pressure upon each lateral extremity, regardless of the angle at which the plane is tipped, thus causing the planes 7 to balance on the center of gravity 3 as a fulcrum, and so rotating the planes 7 into a horizontal position. The center of gravity 3 should lay below the geometric center 15 of the wings 7 for this to take place.

Simultaneously with this the other pair of cross planes 4, which are in a nearly perpendicular position, one at each end, are acted upon by the air in a horizontal direction 2, thus preventing sideslipping. 60 The construction of said cross planes 4 is amplified in the Figs. 1 and 4.

I am aware that changes may be made in the general arrangements and combinations of the various parts, as well as in the 65 details of construction of the said parts, without departing from the scope of the present invention as set forth in the foregoing specifications, and as defined in the clauses of the claims which are appended 70 to the said specifications. Hence, I do not limit my invention to the exact arrangements and combinations of the various parts as described in the said specifications, nor do I confine myself to the said parts as 75 illustrated in the accompanying drawings.

I claim:—

1. An airplane comprising horizontal wings terminating in an upward and downward direction so as to cross, a fuselage, a 80 rudder, and stabilizers adjacent said rudder.
2. An airplane construction comprising a fuselage, horizontal wings mounted adjacent said fuselage, one above the other, and other wings secured to the ends of said horizontal wings projecting upward and downward so as to cross.

3. An airplane comprising a fuselage, stabilizers positioned at the end of said fuselage, a rudder secured adjoining said stabilizers, horizontal wings mounted adjacent said fuselage, and cross wings forming extensions of said horizontal wings in an upward and downward direction so as to 90 cross.

4. An airplane comprising a fuselage, stabilizers positioned on said fuselage, a rudder mounted between said stabilizers, a horizontal wing secured to said fuselage, 100 and auxiliary planes intersecting each other at, or nearly at right angles so as to cross, secured to the lateral extremities of said wing.

5. In an airplane, a horizontal wing, and auxiliary planes secured to the lateral extremities of said wing and intersecting each other substantially at right angles so as to 105 cross.

EDWIN G. GETTINS.
